UNITED STATES PATENT OFFICE.

FRANKLIN E. FRENCH, OF RILEY, INDIANA.

METALLIC RAILWAY-TIE.

No. 888,097.

Specification of Letters Patent.

Patented Dec. 11, 1906.

Application filed July 23, 1906. Serial No. 327,377.

To all whom it may concern:

Be it known that I, FRANKLIN E. FRENCH, a citizen of the United States, residing at Riley, in the county of Vigo and State of Indiana, have invented certain new and useful Improvements in Metallic Railway-Ties, of which the following is a specification, reference being had therein to the accompanying drawings.

10 This invention relates to improvements in metallic cross-ties for railways and to the means for securing the track-rails thereon.

The object of the invention is to improve and simplify the construction of devices of this character, and thereby render the same more durable and efficient.

Further objects and advantages of the invention, as well as the structural features by means of which they are attained, will be made clear by an examination of the specification, taken in connection with the accompanying drawings, in which the same reference-numerals indicate corresponding portions throughout, and in which—

25 Figure 1 is a perspective view of the improved metallic tie. Fig. 2 is a vertical longitudinal section through the same, and Fig. 3 is a detail horizontal section taken on the plane indicated by the line 3 3 in Fig. 2.

30 The improved tie comprises two similar sections 1, preferably cast hollow, of iron or other suitable metal. They are also preferably rectangular in cross-section, as shown, and have tapering inner ends 2, which are

35 externally screw-threaded, as at 3. The threads 3 on one section are right-hand threads and on the other section left-hand, and they are adapted to enter the similarly-threaded openings in the ends of a turnbuckle

40 4, which serves to adjustably connect said sections. Upon the upper faces of the sections 1 are formed transversely-extending undercut shoulders 5, which provide seats 6 for the track-rails. The outer base-flanges 45 of the rails are forced into engagement with the shoulders 5 by clamping members 7, which are adapted to have their undercut outer ends 8 engage the inner base-flanges of the rails, as will be readily understood upon

50 reference to Fig. 2. The clamping members 7 are in the form of substantially triangular-shaped plates, mounted for longitudinal sliding movement upon the tie-sections by reason of the engagement of their downwardly 55 and inwardly bent tongues 8', with longitudinal grooves 9 formed in the sides of said

sections, as clearly shown in the drawings. The tongues 8' are formed integral with the clamping plates or members upon their sides adjacent to their undercut outer ends 8. The 60 opposite or inner ends 10 of the clamping members are tapered and externally screw-threaded, as shown at 11, to enter similarly-threaded openings in a turnbuckle 12, which adjustably connects them. The threads 11 on the two ends 10 are right and left, so that when the turnbuckle 12 is rotated in one direction the clamping members will be forced apart to clamp the track-rails between their ends 8 and the shoulders 5 upon the tie-sections, and when said turnbuckle is rotated in the opposite direction said clamping members will be drawn together and away from the track-rails, so that the latter may be removed from the tie.

75 The construction, operation, and advantages of the invention will be readily understood from the foregoing description, taken in connection with the accompanying drawings. It will be seen that the provision of 80 the turnbuckle 4 between the two tie-sections permits the latter to be adjusted toward and from each other, so that the gage of the track-rails may be varied as desired or corrected when found necessary. The provision 85 of the turnbuckle 12 permits the clamps 7 to be readily operated, so that the rails may be quickly and easily removed from or applied to and clamped upon the tie.

The tie is of simple, strong, and durable 90 construction and may be manufactured at a comparatively small cost.

Having thus described my said invention, what I claim as new, and desire to secure by Letters Patent of the United States, is—

1. A metallic tie comprising sections having oppositely-screw-threaded inner ends, rail-seats upon said sections, rail-clamping members slidably mounted upon said sections and having their inner ends oppositely 100 screw-threaded, a turnbuckle connecting the threaded ends of said clamping members, and a turnbuckle connecting the threaded ends of said tie-sections, substantially as shown and described.

2. A metallic tie comprising sections having oppositely-screw-threaded inner ends and guide-grooves, clamping-plates upon said sections having oppositely-screw-threaded inner ends, tongues on said clamping-plates slidably 110 engaged with said grooves, a turnbuckle connecting the threaded inner ends of said clamp-

ing-plates, and a turnbuckle connecting the threaded inner ends of said tie-sections, substantially as shown and described.

3. A metallic tie comprising sections having rail-seats, means connecting said sections for adjusting them toward and from each other, rail-clamping members for holding the rails upon the rail-seats on said tie-sections, and means connecting said rail-clamping members for adjusting them toward and

from each other, said rail-clamp connecting and adjusting means being independent of said tie-section connecting and adjusting means, substantially as shown and described.

In testimony whereof I hereunto affix my 15
signature in presence of two witnesses.

FRANKLIN E. FRENCH.
